UNITED STATES PATENT OFFICE.

FRITZ K. HOHENSTIEN AND CHARLES G. MEYERS, OF RICHMOND, INDIANA.

AIR-PUMP.

1,074,051.

Specification of Letters Patent. Patented Sept. 23, 1913.

Application filed December 11, 1912. Serial No. 736,187.

To all whom it may concern:

Be it known that we, FRITZ K. HOHENSTIEN and CHARLES G. MEYERS, citizens of the United States, residing at Richmond, in the county of Wayne and State of Indiana, have invented certain new and useful Improvements in Air-Pumps, of which the following is a specification, reference being had to the accompanying drawings.

10 This invention relates to air pumps, and is particularly adapted for use with the cylinder of a motorcycle engine, and an object of the pump is to provide means whereby the tires of the motorcycle may be inflated 15 upon the reciprocation of the engine piston.

A further object of the invention is the provision of an air pump which may be quickly and easily attached to or detached from the cylinder of an engine.

20 A still further object of this invention is the provision of an air pump comprising a cylinder having a piston mounted for reciprocation therein, the cylinder being adapted for connection with the spark plug opening 25 of the engine cylinder, the movement of the piston of the pump being dependent upon the reciprocation of the piston of the engine.

With these and other objects in view, our 30 invention resides in the novel construction and arrangement of parts to be hereinafter more fully described, claimed and illustrated in the accompanying drawing, in which,

Figure 1 is a longitudinal section of the pump showing it applied to the cylinder of 35 an engine. Fig. 2 is a fragmentary section of the piston connection. Fig. 3 is a section taken on the line 3—3 of Fig. 4. Fig. 4 is a fragmentary elevation of the piston connection.

40 Referring more particularly to the drawing, the numeral 1 designates the cylinder of a motorcycle engine, the cylinder being of any desired construction in which is mounted a piston 2, the cylinder having the 45 usual spark plug opening 3, in which is inserted one end of an elbow 4. The air pump, comprises a cylinder 5 which is formed at one end with a neck 6, the neck being adapted to enter the opposite end of the elbow 4, 50 and being formed with an opening 7 in one side for the reception of a spark plug which

may be of any suitable construction. The opposite end of the cylinder 5 is exteriorly threaded as at 9 for the reception of an interiorly threaded flange 10 of one end of 55 another cylinder 11. A piston 12 is mounted for reciprocation in the cylinder 5 and suitable piston rings 13 are mounted on the periphery of the piston to form a tight joint between the cylinder and the piston. A 60 similar piston 14, having piston rings 15, is mounted for reciprocation in the cylinder 11 and connecting the pistons 12 and 14 is a suitable piston rod 16. Suitable buffer springs 17 are mounted upon the head 18 of 65 the cylinder 5 and the head 19 of the cylinder 11 to form cushions for the piston 12 at either end of its stroke. The outer end of the cylinder 11 is exteriorly threaded as at 20 for the reception of the threads 21 of the 70 cylinder cap 22, which is provided with suitable openings 23 for the ingress and outlet of air. Suitable openings 24 and 25 respectively are formed in the outer head of the cylinder 11, and an inwardly opening 75 check valve 26 is disposed in the opening 24 and secured in the outlet opening 25 is one end of an air hose 27 in which is mounted a ball valve 28 which is adapted to normally close the opening 25.

80 It will be understood that our invention is adapted to be secured in the spark plug opening of an engine of the four cycle type and upon the downward or aspirating stroke of the engine piston 2, the pistons 12 and 14 85 will be drawn toward the inner ends of the cylinders 5 and 11 respectively by reason of the suction in the cylinders caused by the movement of the piston 2, and air will be drawn into the cylinder 11 through the inlet 90 opening 24 of the cylinder. Upon the upper or compression stroke of the piston of the engine, the pistons 12 and 14 are moved outwardly whereupon the supply of air in the piston 11 is forced out through the outlet 95 opening 25 into the air hose 27 and thence into the tire (not shown). Upon the second downward or explosive stroke of the piston 2, the piston 12 acts as a reactionary member, and remains stationary against the inner 100 head 19 of the cylinder 11, while the piston 2 is moved downwardly by reason of the

force of the explosion. Upon the fourth cycle of the engine, the piston 2 is moved upwardly whereupon the burned gases are forced out of the cylinder, and then the operation of the pump is repeated.

It is apparent that upon the fourth cycle or exhaust stroke of the piston 2, a portion of the burned gases will be forced into the cylinder 5 of the pump, and to allow the burned gases to escape from the cylinder through the outlet ports 29 in the head 19 of the cylinder 11, we have provided a flexible connection between the pistons 12 and 14. This flexible connection comprises the hollow piston rod 16 which is rigidly secured in the piston 12 and extends to the piston 14, and a solid piston rod 30, which is secured to the piston 14, extends for a short distance into the outer end of the hollow piston rod 16. A spiral contractile spring 31 is connected at one end to the outer end of the piston 30 and its opposite end to a cross bar 32 in the piston rod 16. The longitudinal slots 33 are formed in the hollow piston rod near the outer end thereof, and extending from the piston 14 in a sleeve 34 which encircles the hollow piston rod 16 so as to close the slots therein. A pin 35 is secured in the piston rod 30 and the opposite ends thereof extend through the slots 33 and are secured in the opposite sides of the sleeve 34 to limit the sliding movement of the piston 14 with relation to the piston rod 16. It will be seen that upon the exhaust stroke of the piston 2, the burned gases which enter the cylinder 5 will be forced into the hollow piston rod 16 against the inner face of the piston 14, and will tend to move the piston 14 away from the outer end of the hollow piston rod 16 against the action of the spring 31. It will be seen that upon the outward movement of the piston 14, the sleeve 34 will be moved outwardly on the piston rod 16 and uncover the slots 33 through which the gases will flow and escape through the exhaust ports 29. When the piston 2 has completed its upward stroke and the gases have been exhausted from the cylinder 11, the action of the spring 31 will tend to draw the piston 14 against the upper edge of the hollow piston rod 16, and the sleeve 34 will close the openings 33 in the rod 16 and the pump is then ready for another operation.

In view of the above description, taken in connection with the accompanying drawing, it will be seen that we have provided an air pump which is adapted for use with the cylinder of an explosive engine and which requires a minimum number of parts, which may be cheaply constructed and which will fulfil all the requirements of such a device.

While the construction illustrated in the

accompanying drawing is the preferred embodiment of our invention, it will be understood that many minor changes may be made in the details of construction without departing from the spirit of the invention or sacrificing any of its advantages, as determined by the scope of the appended claims.

Having thus fully described our invention, what we claim and desire to secure by Letters Patent is:

1. A pump comprising a cylinder, inlet and outlet ports formed in said cylinder, spaced pistons mounted for reciprocation in said cylinder, one of said pistons having an opening therein, a hollow piston rod mounted within said opening at one end and extending to the other of said pistons, said hollow piston rod being formed with longitudinal slots near its free end, a sleeve connected to said other piston and adapted to encircle the free end of said hollow piston rod and extend over the slots therein, and flexible means connecting said other piston with said hollow piston rod to normally maintain said sleeve over said slots, as and for the purpose described.

2. A pump comprising a cylinder, inlet and outlet ports formed in said cylinder, spaced pistons mounted for reciprocation in said cylinder, one of said pistons having an opening therein, a hollow piston rod mounted within said opening at one end extending to the other of said pistons, said hollow piston rod being formed with longitudinal slots near its free end, a sleeve connected to said other piston and adapted to encircle the free end of said hollow piston rod and extend over the slots therein, a pin mounted in the walls of said sleeve and projecting through said slots to limit the separation of said pistons, and a spring connected to said other piston and to the hollow piston rod to normally maintain said sleeve over the slots in said hollow piston rod, as and for the purpose described.

3. A pump comprising a cylinder, inlet and outlet ports formed in said cylinder, spaced pistons mounted for reciprocation in said cylinder, one of said pistons having an opening therein, a hollow piston rod mounted in said opening at one end and extending to the other of said pistons, a solid piston rod connected to said other piston and extending within said hollow piston rod, and a spring connected to said piston rods for holding said other piston in engagement with the outer end of said hollow piston rod, as and for the purpose described.

4. A pump comprising a cylinder, inlet and outlet ports formed in said cylinder, spaced pistons mounted for reciprocation in said cylinder, one of said pistons having an opening therein, a hollow piston rod mount-

ed within said opening at one end and extending to the other of said pistons, a piston rod connected with said other piston and disposed within the free end of said hollow piston rod, the free end of the hollow piston rod being formed with longitudinal slots, a sleeve connected with said other piston and adapted to encircle the free end of said hollow piston rod and extend over the slots therein, and means for connecting said piston rods to normally hold said other piston

against the free end of the hollow piston rod, as and for the purpose described.

In testimony whereof we hereunto affix our signatures in the presence of two witnesses. 15
